UNITED STATES PATENT OFFICE.

JOSEPH SCHWEISS, OF ST. LOUIS, MISSOURI.

DEFLECTION-INDICATOR.

1,238,578.

Specification of Letters Patent. Patented Aug. 28, 1917.

Application filed February 21, 1917. Serial No. 150,058.

To all whom it may concern:

Be it known that I, JOSEPH SCHWEISS, a citizen of the United States, residing at the city of St. Louis, State of Missouri, have invented a certain new and useful Improvement 5 in Deflection-Indicators, of which the following is a full, clear, and exact description, such as will enable others skilled in the art to which it appertains to make and use the same, reference being had to the accompanying drawings, forming part of this specification.

This invention relates generally to tools and machines for metal working, and specifically 15 to a testing device adapted for use in the various forms of machines, such as milling machines, for the placing, spotting or locating of the work in the machine in proper relationship to the tool which is designed 20 to operate upon it.

As is well known in the art of metal working, various forms of machines are employed wherein the work is mounted on a work holder, and a tool is mounted on a chuck or 25 tool holder in proper position for operation upon the desired portions of the work. As the relative movement of the tool and the work is rendered automatic by the operation of the machine, it is essential, in order to 30 insure the proper application of the tool to the work and the consequent proper forming of the latter, that the work be definitely and accurately located with reference to the tool and its axis of operation.

The device comprising my invention is 35 designed as a test indicator which may be suitably mounted on the tool carrier so that the movement of the latter will trace the course of the tool relative to the work. A portion 40 of the device is designed to make contact with a surface of the work throughout the movement of the tool holder, and from this coöperation of the device with the work, the relative position of the two is rendered evident 45 to the operator through suitable indicating means. Such devices are not broadly new, and my invention consists essentially in a novel and improved form of device for accomplishing this operation.

It is the principal object of my invention 50 to provide a device of the type described which is constructed so that its indicating portions may be in full view and readily observed by the operator at all positions of the device when it is in use in tracing the intended contour.

A further object is to provide a device which is capable of very fine construction so that exceedingly nice and accurate work may be accomplished by it, and at the same time 60 maintain such strength and simplicity in the construction as will render the instrument thoroughly practical.

Other objects will be obvious or pointed out hereinafter, reference being had to the 65 accompanying drawings, in which—

Figure 1 may be considered either a plan or an elevational view of the device as it would appear mounted in a holder on a machine;

Fig. 2 is a longitudinal sectional view of the instrument; and

Fig. 3 is a cross sectional view taken on the line 3—3 of Fig. 2.

The embodiment of the invention illustrated in these drawings consists in the first place of a tubular body portion 1 which tapers to its outer extremity from a larger generally cylindrical head portion 2. The body portion 1 is formed with a longitudinal tapering channel-way 4 which is closed for the most part by a plug or disk member 5. Fixed on this disk member 5 and located on the longitudinal axis of the body portion, is a pivot member 6. On one side 80 of this pivot member, the disk member 5 is provided with an aperture 7 extending across more or less of the width of the channel 4 and providing space for the passage and operation of a rod 8. This rod forms 85 one arm of a lever which is pivoted at 9 near the outer extremity of the body portion on pivot members 10, and the other arm of said lever is formed by a finger member 11 which extends out of the forward 90 end of the body member and is curved or deflected to one side thereof, where it terminates in a bearing extremity 12. When this lever is rocked or vibrated by manipulation of the finger portion 11, the rod portion 8 is 95 oscillated in the aperture 7. Mounted on the head portion 2 is a cap member 14 which is in the form of a spider member with legs 15 which engage the head member 2 to hold the diaphragm portion 16 spaced apart from 100 the head portion 2. On the diaphragm portion 16 is carried a pivot member 17 which is coaxially alined with the pivot member 6. Between and upon these pivot members 6 and 17 is rotatably mounted an indicator 110 disk 18 which is spring-pressed in one direction by a light spring 19, which is attached

at one end to said disk, and at the other end to the fixed disk member 5. At different points about its periphery, the indicator disk 18 is provided with indicating fingers 5 20 which are designed to coöperate with the curved face of the head member 2 intermediate the leg portions 15 of the spider member, which curved surface of the head member is calibrated with suitable scales 21. 10 The free extremity of the rod 8 has operative connection with the indicator disk 18 to one side of the pivot members 6 and 17, in the form shown said connection being made by the end of the rod 8 passing 15 through an aperture in the disk 18. The length of the slot 7 in the member 5 permits the desired extent of movement of this end of the rod 8 when the lever member of which it forms a part is rocked on its pivot 20 formed by the pivot members 10. By virtue of this arrangement of parts, whenever the lever member is rocked by application of pressure to the finger portion 11, the indicator disk 18 will be rotated on its pivot in 25 proportion to the movement of the lever, and the degree of rotation of the disk may be observed by reference to the scales 21. Upon removal of the operating pressure from the finger portion 11, the indicator disk is moved 30 toward normal position by the lightspring 19.

In the use of the device, the instrument is mounted in a suitable holder A which is carried on some movable portion B identified with the tool holding part of the machine. 35 The piece of work which is being placed in the machine having been mounted on the chuck or work holder, the contact member 12 of the instrument is brought into tactile association with the surface whose contour 40 is to be used as the guide for locating the work. Then when the tool and work carrying portions of the machine are given the intended relative rotation, the instrument will trace along the test surface of the 45 work so that any deflection of the latter from the proper working axis will cause a proportionate movement of the lever member and the consequent indication by movement of indicator disk 18. As the instrument 50 is moved about the work axis, one or another of the scales 21 will be directly visible at all times to the operator, so that the test may be accurately followed and the location of the work accomplished with 55 precision and speed.

Having thus described and shown what I now believe to be the best embodiment of my invention and one which has been put into successful practice, I am aware that the 60 same is not the only possible form, and that it may be modified and altered in various particulars without departing from the true and essential scope of the invention which I intend to indicate in the following claims.

What I claim is:

1. An indicating instrument including a lever member mounted for coöperative association with a guiding surface, an indicator disk pivoted for rotation on an axis extending substantially at right angles to the pivotal axis of the lever, indicating portions carried by said disk and extending substantially parallel with and on different sides of the pivotal axis of the disk, and there being indicia visibly associated with said indicating portions; said lever and said disk being operably associated whereby the latter is rotated upon oscillation of the former. 75

2. In an instrument of the class described, 80 the combination of a body portion, means for mounting the body portion for revolution, the body portion being provided with peripherally disposed graduation marks forming a scale, actuating means extending longitudinally of the body portion and arranged at its outer extremity for coöperation with a guiding surface, and an indicating member movably supported on the body portion and extending into coöperative 85 association with the scale, there being operative connection between the actuating means and said indicating member whereby the latter is moved relative to the scale upon 90 actuation of the former. 95

3. An instrument of the class described, comprising a body member of general tubular form provided with actuating means arranged at one extremity of the body member for coöperation with a guiding surface, said body member being provided adjacent its other extremity with graduation marks forming scales about the periphery thereof, there being indicating members carried by the body portion adjacent said last mentioned extremity and extending longitudinally of said body member into coöperative association with the graduation marks thereon, and there being operative connection between the actuating means and said indicating members whereby the latter are moved relative to the scales upon actuation of the former. 100 105 110

4. An instrument of the class described comprising a body member of general frusto-conical form, actuating means mounted thereon and arranged adjacent the outer extremity of said body member for coöperation with a guiding surface, the lateral surface of the body member adjacent its other extremity being provided with graduation marks forming scales peripherally disposed on different sides of the axis of the body member, and indicating members movably mounted on the body portion and arranged for association with graduation marks on different sides of the axis of the latter, there being operative connection between said in- 115 120 125

dicating members and actuating means whereby the former are moved upon actuation of the latter.

5. An instrument of the class described including a body member of general tubular form, an indicator disk mounted at one extremity thereof and revoluble substantially upon the longitudinal axis thereof, actuating means mounted on the body member and 10 extending longitudinally thereof, the outer extremity of said actuating means being adapted for coöperation with a guiding surface exterior of the body member and the

inner extremity of said guiding means having operative connection with the indicator 15 disk, the body member being provided with graduation marks peripherally disposed on the outer surface thereof adjacent the indicator disk, and there being indicating members carried by the indicator disk and movable therewith in coöperative association with the graduation marks on different sides of the axis of the body member.

In testimony whereof I hereunto affix my signature this 19th day of February, 1917.

JOSEPH SCHWEISS.
